(57) **CLAIM**

The ornamental design for an digital camera with image display, as shown and described.

DESCRIPTION

FIG. 1 is a front view of a digital camera with image display showing our new design; and, FIG. 2 is an enlarged view of the image display on the digital camera in FIG. 1.

The broken line showing of the digital camera in FIG. 1 represents portions of the design which form no part of the claimed design.
